CARTON FEEDING AND SQUARING-UP DEVICE

Donald C. Anderson, North College Hill, Ohio, assignor to The Procter & Gamble Company, Cincinnati, Ohio, a corporation of Ohio

Application January 25, 1955, Serial No. 484,032.

15 Claims. (Cl. 93—53)

The invention is directed primarily to means for removing collapsed cartons from a stack or assembly and squaring-up or opening the tubular bodies thereof, especially as a part of a filling machine in which the cartons will be closed at one end, inverted if necessary, filled with a measured quantity of contents, and closed on the remaining end.

As is well known, cartons for the general purpose described come to the filling machine in "folded and glued" condition, i. e. with tubular bodies in the collapsed form, there being closure flaps articulated to the ends of the body walls. The collapsed cartons are placed on the machine in groups or assemblies, frequently called "stacks." The machine acts to remove the cartons individually from the stack, an operation herein termed "feeding." Then the tubular bodies are erected, an operation termed "squaring-up" herein, and are placed between abutments or blocks on a traveling conveyor, after which the other operations mentioned above are performed on them.

Hitherto the mechanisms for feeding and squaring-up cartons have constituted a bottleneck in the operation of filling machines, so that it is a primary object of the present invention to provide means for feeding and squaring-up cartons which are adapted to positive operation at high speeds.

For example, existing devices for feeding collapsed cartons from a stack frequently embody suction cups which are pressed against the foremost carton and pull it away from the stack. Such devices are of a reciprocating nature, are difficult to maintain, and have a top speed not exceeding about 300 cartons per minute. An object of this invention is to provide a feeding means of non-reciprocating character, having continuous motion, and acting to feed cartons from a stack at very much greater speeds, e. g. in the neighborhood of 500 per minute, or more.

Devices for squaring-up cartons have hitherto had similar disadvantages. Frequently they operate by the use of means which, moving the carton forwardly against a stop traveling at a lesser speed, exerts a squaring-up pressure on the carton body. Such devices are again difficult to maintain and tend to be impulsive in action particularly at high speeds, for which reason marring and sometimes a crumpling of the cartons results. It is an object of the invention to provide a smoothly acting, continuously moving, means for squaring-up cartons to the extent that they may be delivered between the abutments of a traveling conveyor without these disadvantages, and at high speeds.

It is an object of the invention to provide a continuously moving means which serves the combined functions of feeding and squaring-up the carton bodies while minimizing contact with outside portions of the cartons.

These and other objects of the invention, which will be set forth hereinafter or will be apparent to one skilled in the art upon reading these specifications, are accomplished by that procedure and in the use of that mechanism of which certain exemplary embodiments will now

be described. Reference is made to the accompanying drawings wherein:

Fig. 1 is a partial plan view of mechanism constituting essential elements of the apparatus invention.

Fig. 2 is a side elevation thereof.

Fig. 3 is a partial perspective view of a plurality of collapsed cartons at the feeding end of a stack, together with attendant mechanism.

Fig. 4 is a partial elevational view with portions in section, showing the plucking end of the feeding and squaring-up mechanism about to become engaged with the end carton in a stack.

Fig. 5 is a partial sectional view showing the engagement of a feeding and squaring-up element with a carton while the squaring-up operation is in progress.

Fig. 6 is a partial elevational view of a modified mechanism in accordance with the invention.

In the drawings the cartons have been illustrated as structures having tubular bodies and conventional seal-end flaps. It will be understood that the apparatus and method, herein described are applicable to modified carton structures with various forms of closure flaps, cartons with the so-called Van Buren ears, and others. The drawings have further been restricted to those mechanical elements which are necessary to the understanding of the invention. Thus, machine frame elements have been shown partially in some figures, and omitted in others; drive elements have not been illustrated, as such, and no portions of the carton filling and closing machine have been shown excepting those parts with which the invention, hereof is directly concerned. Non-illustrated matters are well known in the art or are within the skill of the worker therein to construct in the light of the teachings which follow.

Briefly, in the practice of the invention, it has been found possible to pluck or remove cartons individually from a stack and to cause them to travel along a pathway wherein they are squared-up for delivery between the abutments of a moving conveyor, by a unitary means in the form of a continuously rotating helix which changes both pitch and width along the path. A single helical element may be employed for the purpose, but commonly a helical element is provided at each end of the cartons. One at least of the helical elements, engaging within the cartons so as to avoid contact with outer surfaces thereof, serves to pluck a carton from a stack, carry it along the path, and open or square it up so as to deliver it to the receiving conveyor. Where a second helical element is employed, it may do likewise, or it may be employed primarily as a moving guide, as hereinafter described. As the cartons are moved in the aforesaid path and are squared up by the helical element or elements, they are tilted, so that their major transverse body axis lies astant to their direction of motion in the path. This brings them at the end of the path, into a position to be engaged between the blocks or abutments on the receiving conveyor as the conveyor is following a non-rectilinear path, for example, a return path about a sprocket. Hence, as the squared-up cartons are delivered to the conveyor, the blocks or abutments between which they are received are in a slightly radially separated condition. Thereafter, in a straight flight of the receiving conveyor, the blocks come into parallel relationship, accurately completing the squaring-up of the carton bodies.

Referring, first, to Figs. 1 to 5, cartons are illustrated having body walls 1 and 2 and closure flaps 3 and 4, the flaps 3 being the relatively large closure flaps on the wide body walls 1, and the flaps 4 being the relatively shorter flaps on the narrow body walls 2. The cartons form a stack 5 at the entrance end of the machine. In the embodiments illustrated, the stack rests upon a lower support 6 and is confined between one or more rear rails

or guides 7 and one or more front guides 8. A forward pressure is exerted upon the stack, as may be accomplished in various ways. If the machine is arranged vertically, the forward pressure may be the effect of gravity. If the machine is arranged horizontally as illustrated, a resilient abutment (not shown) may be placed behind the cartons in the stack or a traveling conveyor may lie to the right of the support 6, underlying a portion of the stack and exerting forward pressure thereon. To prevent the cartons from leaving the stack prematurely, one or more fingers 9 and 10 are provided. It will be seen in Figs. 2 and 3 that the bent-over ends of these fingers miss the short flaps 4 but engage flaps 3 on the trailing side of the collapsed carton which is about to be fed. The forward pressure on the stack causes a slight opening up of the tubular carton body.

In the embodiment of Figs. 1 to 5, a pair of shafts 11 and 12 are so journaled as to lie one above and one below the cartons in the path. These shafts are driven by suitable means in timed relationship. Each shaft bears also a helical member 13 or 14 mounted by means of suitable radial studs on the shaft so as to rotate with it. At the feeding end these helical members are quite thin, preferably having the blade-like configuration most clearly illustrated at 15 in Fig. 4. Toward the opposite ends of the shafts 11 and 12, the helical members 13 and 14 not only change progressively in pitch, but also progressively in width, so that at the point where the cartons are delivered to the abutment conveyor, the helical members have attained a width substantially equal to the distance between the wide body walls 1 in the squared-up carton structure.

The helical members 13 and 14 are of substantially constant circumference throughout their length; and the shafts 11 and 12 are so spaced from each other that the distance between the helical members at their nearest points will be somewhat less than the lengths of the body walls of the cartons. It will be within the skill of the machine designer to provide for adjustment of the positions of the shafts 11 and 12 to accommodate cartons of different lengths, as well as for the substitution of other helical members for handling cartons of different body sizes.

Fig. 4 shows how the thin end of a helical member 13, turning clockwise in the direction of the arrow will enter between the flaps of a carton at the plucking end of the stack. Fig. 5 is illustrative of the fact that as the rotation of the helix continues, it will engage between the body walls of the carton, as at 13a. Due to the pitch of the helical member, the carton so engaged is moved away from the stack and pulled out from between fingers 9 and 10, giving a positive feeding action produced by means engaging inner rather than outer surfaces of the carton.

It will be understood that the shafts 11 and 12 rotate oppositely to each other but at the same speed, with the helices properly oriented thereon. As a consequence, when a carton has been removed from the stack, it will be moved along a path of travel parallel to the shafts. By reason of the increase in pitch of the helical members in the direction of this movement, the individual cartons will be tilted more and more in the direction of travel, as will be apparent in Figs. 1 and 2. Moreover, as the cartons move in the path, they will be progressively opened and squared-up because of the increasing width of the helical members engaging between the body walls of the cartons. Depending upon the direction of rotation of the shafts, there will be a net resultant of force on the cartons transverse the shafts, and for this reason the guide elements 7 are continued along the path of travel, being slanted toward the plane of the shafts to compensate for the lessening of the effective width of the carton bodies as they are both tilted and squared-up. This is clearly shown in Fig. 1.

The receiving conveyor is shown as comprising chains

75 a cone instead of on the surface of a cylinder. It will

16 traveling about sprockets, one of which is partially illustrated in Fig. 1 at 17. The chains bear abutments or blocks 18, spaced at intervals corresponding to the effective width of the squared-up carton bodies. When a carton body is delivered and released by the helical members 13 and 14, it will be in substantially fully squared-up condition and in such position as to pass behind a guide member 19 and come into place between a pair of adjacent abutment members or blocks 18, as most clearly apparent in Fig. 1. Since the chains 16 are at this point moving about the circumference of sprockets, the adjacent abutments will not be parallel but will be angularly related as shown. The carton bodies will be substantially squared-up as delivered to the conveyor, sufficiently so that they will come easily between the abutments in the positions shown. Afterwards, in the straight away flight of the conveyor, the abutments will come into parallelism, not only completing the accurate squaring-up of the carton bodies, but also engaging them in such fashion as to carry them through other operations performed by the filling machine.

Modifications may be made in the invention without departing from the spirit of it. By way of example, a modification is illustrated in Fig. 6 wherein like parts have been given like index numerals. In this embodiment the shafts 11 and 12 bear helical members 20 and 21 made of wire or rod-like material. The cartons are again held in a stack 5 under the same conditions and 25 by the same mechanism that has been described above. The forward narrow end 22 of the lower helix 21 enters the carton about to be removed from the stack as hereinabove described, and moves its end of the carton away from the stack as illustrated in dotted lines at 23. Farther along in the direction of the length of the helical member 21, it becomes double, i. e. a second rod-like helix 21a begins and roughly parallels the helix 21. But as the convolutions of the helical members progress, the member 21a increases its distance from the member 21 until, at the far end of the helical member, the rods are spaced from each other substantially the distance between the wide walls of the erected carton. In other words, the second rod-like helix 21a gradually diverges from helix 21 so that the two together form the two edges of an imaginary surface equivalent to the ribbon 13 in Fig. 1. This is illustrated at points 24 and 25 in Fig. 6.

The upper helix 20 may, if desired, be the same as (a mirror image of) the lower helix 21 and 21a, in which event the operation of the helices will be the same as that hereinabove described in connection with Figs. 1 to 5 inclusive. However, in Fig. 6 there is illustrated a modification in which the upper helix 20 is a single rod helix lacking a nose portion similar to 22 for entering the top part of the carton body. It is the lower helix 21, therefore, which removes the carton from the stack, and it does so in a tilted position, as shown in dotted lines at 23. In this embodiment, on the shaft 12 a second helix 26 is mounted. This helix is of larger diameter than the helix 21. It engages behind the carton removed from the stack and straightens it up into substantially vertical position, as shown at 27. In this position the carton comes against the helix 20.

The first convolutions of the helix 20 in Fig. 6 have a high pitch, and as a result of the operation of the apparatus, the remaining convolutions come behind or on the trailing side of the carton, as at 27a, acting thereafter to maintain the carton in an upright position against the guide elements 7, 7, although the upper helix in this particular embodiment does not enter the carton. The helical members herein described need not be of constant diameter throughout their length. They may, for example, progressively decrease in diameter from the plucking end to the carton feeding end, i. e. as though the helices were formed on the surface of a frustum of a cone instead of on the surface of a cylinder. It will

be understood that as the helices widen, a smaller effective diameter permits them to enter more deeply between the opposite walls of the carton and therefore to exert a more positive squaring-up effect.

Other modifications may be made in the invention without departing from the spirit of it. The invention having thus been described in certain exemplary embodiments, what is claimed as new and is desired to be secured by Letters Patent is:

1. In a device for squaring-up collapsed cartons, a shaft, a helical element mounted on said shaft to be rotated thereby, one end of said helical element being adapted to enter the collapsed body of a carton between opposed walls thereof and by engagement with said carton to move it along a path, and means along said path to maintain contact between said carton and said helical element while it is being so moved, the convolutions of said helical element extending away from said mentioned end having a progressive increase in width in a direction substantially axially of said helical element, whereby the said convolutions act to exert internal expanding pressure on opposed walls of the carton to square it up while moving it in said path.

2. The structure claimed in claim 1, wherein one of the means for maintaining contact of said carton with said helical element is a second helical element mounted on a driven shaft.

3. The structure claimed in claim 1, wherein one of the means for maintaining contact of said carton with said helical element is a second helical element mounted on a driven shaft, said last mentioned helical element being of opposite hand to said first mentioned helical element, and said second mentioned shaft being driven oppositely to said first mentioned shaft, and wherein another of said means comprises at least one side guide located to resist a transverse thrust exerted upon said carton by means of said helical elements.

4. The structure claimed in claim 3, wherein both helical elements enter the body of said carton between opposed walls thereof.

5. The structure claimed in claim 3, wherein both helical elements enter the body of said carton between opposed walls thereof, and in which both helical elements increase in width in successive convolutions.

6. In a device for squaring-up collapsed cartons, a shaft, a helical element mounted on said shaft to be rotated thereby, one end of said helical element being adapted to enter the collapsed body of a carton between opposed walls thereof and by engagement with said carton to move it along a path, and means along said path to maintain contact between said carton and said helical element while it is being so moved, the convolutions of said helical element extending away from said mentioned end having a progressive increase in width in a direction substantially axially of said helical element, whereby the said convolutions act to exert internal expanding pressure on opposed walls of the carton to square it up while moving it in said path, said helical element also increasing in the pitch of its convolutions extending away from said mentioned end, whereby the carton is progressively turned axially while moving in said path.

7. In a device for squaring-up collapsed cartons, a shaft, a helical element mounted on said shaft to be rotated thereby, one end of said helical element being adapted to enter the collapsed body of a carton between opposed walls thereof and by engagement with said carton to move it along a path, and means along said path to maintain contact between said carton and said helical element while it is being so moved, the convolutions of said helical element extending away from said mentioned end having a progressive increase in width in a direction substantially axially of said helical element, whereby the said convolutions act to exert internal expanding pressure on opposed walls of the carton to square it up while moving it in said path, in combina-

tion with means for presenting a carton in collapsed condition to the mentioned end of said helical element and means for receiving and holding said carton in squared-up condition at the opposite end of said helical element when the carton is released thereby.

8. In a device for squaring-up collapsed cartons, a shaft, a helical element mounted on said shaft to be rotated thereby, one end of said helical element being adapted to enter the collapsed body of a carton between opposed walls thereof and by engagement with said carton to move it along a path, and means along said path to maintain contact between said carton and said helical element while it is being so moved, the convolutions of said helical element extending away from said mentioned end having a progressive increase in width in a direction substantially axially of said helical element, whereby the said convolutions act to exert internal expanding pressure on opposed walls of the carton to square it up while moving it in said path, in combination with means for presenting a carton in collapsed condition to the mentioned end of said helical element and means for receiving and holding said carton in squared-up condition at the opposite end of said helical element when the carton is released thereby, said last mentioned means being a conveyor having spaced abutments thereon between which said carton is received in squared-up condition.

9. The structure claimed in claim 8, wherein the pitch of the convolutions of said helical element extending away from said first mentioned end increases progressively so that said carton is turned in the axial direction as it is moved in said path, and wherein the said receiving conveyor moves in its receiving portion at an angle to said path appropriate for the reception of the carton in its turned position.

10. A carton opening and feeding mechanism comprising a helical ribbon mounted for rotation on a horizontal axis below the lower end of the carton feed position, said ribbon beginning with a knife-like extension at the plucking end, said knife-like extension being adapted to be pushed into the bulge of the lead carton at the downward end thereof said bulge resulting from the carton being held by a stop affecting its rearward wall, the ribbon helix having a low pitch and narrow ribbon width immediately adjacent to the knife blade and thereby being adapted to follow said knife blade into the carton, said ribbon helix as it extends away from the plucking end becoming increasingly greater in pitch and ribbon width until such width approaches the thickness of an opened carton and means for plucking the lead carton from the stop at the top of said lead carton and helical means for guiding and propelling the top of the plucked cartons, the length and pitch of the helices being such as to deposit the cartons in opened condition, as a carton filling belt is reached, upon said belt at a suitable angle as said belt travels around a sprocket wheel, said filling belt, plucking means and helical ribbons being driven in timed relationship to insure the carton being placed upon the filling belt in linear relationship to carton spacing means thereon.

11. The carton opening and feeding mechanism of claim 10, in which the means for plucking the lead cartons from the stop at the top of said lead carton and the helical means for guiding and propelling the top of the plucked cartons are combined in a helical ribbon that is a mirror image of the bottom helix.

12. The carton opening and feeding mechanism of claim 10, in which the means for plucking the top of the lead carton is a short helix of larger diameter affixed to the lower ribbon-like helix and the means for guiding and propelling the tops of the cartons is a simple helix of varying pitch.

13. A carton opening and feeding mechanism comprising a pair of helical ribbons one mounted for rotation on a horizontal axis below the lower end of the cartons,

and one mounted for rotation on a horizontal axis above the upper end of the cartons, said ribbons beginning with knife-like extensions, at the plucking end, said knife-like extensions being adapted to be pushed into the bulge of the lead cartons at the upper and downward ends thereof, the ribbon helices having a low pitch and narrow ribbon width immediately adjacent to the knife blades and thereby being adapted to follow such knife blades into the carton, said ribbon helices as they extend away from the plucking end becoming increasingly greater in pitch and in ribbon width until such width approaches the thickness of an opened carton, whereby the cartons are in open condition as a carton filling belt is reached, the length and pitch of the helices being such as to deposit the cartons on said carton filling belt at a suitable angle as said belt travels around a sprocket wheel, said filling belt and helical ribbons being driven in timed relationship to insure the cartons being placed upon the filling belt in linear relationship to carton spacing means thereon.

14. In combination, a means for presenting an assemblage of cartons having collapsed tubular bodies and end closure flaps, retaining means at the end of said first mentioned means engaging a trailing flap of the leading carton, and a continuously moving helical element having a trailing end shaped and positioned to enter between the flaps of said leading carton and opposed body walls thereof and pluck said carton away from said first mentioned means, and means for maintaining contact of said

5
10
15

25

carton with said helical element, the convolutions of said helical element increasing progressively in width as they extend away from said mentioned end, whereby during the continued engagement of said carton with said helical element and its movement in said path thereby, the collapsed body of said carton is squared up.

15. In combination, a means for presenting an assemblage of cartons having collapsed tubular bodies and end closure flaps, retaining means at the end of said first mentioned means engaging a trailing flap of the leading carton, and a continuously moving helical element having a trailing end shaped and positioned to enter between the flaps of said leading carton and opposed body walls thereof and pluck said carton away from said first mentioned means, and means for maintaining contact of said carton with said helical element, the convolutions of said helical element increasing progressively in width as they extend away from said mentioned end, whereby during the continued engagement of said carton with said helical element and its movement in said path thereby, the collapsed body of said carton is squared up, and means for receiving and retaining said carton in squared up condition at the end of said path.
